UNITED STATES PATENT OFFICE.

CHARLES L. GEORGE, OF FINDLAY, OHIO.

TRENCHING EXCAVATOR.

Application filed March 1, 1924. Serial No. 696,294.

This invention relates to excavators of that type used primarily for digging trenches. In trenching machines utilizing a boom carrying digger mechanism it has been the practice to depend upon the weight of the boom and the mechanism carried thereby for maintaining the boom at the proper angle to insure digging to the desired depth. While this arrangement is effective while the machine is digging through light soil, the cables supporting the boom usually become slackened and the boom swings upwardly if the soil is hard and sufficiently resistant to the action of the digging mechanism. Thus it has been difficult to dig uniform depth through hard soil.

It is an object of the present invention to provide a simple and efficient means for holding the boom of the digging mechanism at any angle to which it may be adjusted thus insuring the production of a trench of uniform depth irrespective of the nature of the soil through which the cut is being made.

A further object is to provide a beam holding mechanism which can be applied readily to excavating machines already in use.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings the preferred form of the invention has been shown.

In said drawings—

Figure 1 is a side elevation of a portion of a digging mechanism embodying the present improvements, a portion of the body of the machine being indicated by broken lines.

Fig. 2 is a plan view of a portion of the boom and its holding mechanism, the segmental racks being shown in section.

Referring to the figures by characters of reference A designates generally the frame of a trench digging machine. A shaft 1 is supported thereby and pivotally mounted on this shaft is a boom 2 adapted to be adjusted

angularly by a cable such as shown at B. An endless belt 3 is carried by the boom and has secured to it a series of digging buckets 4 of the usual or any preferred type.

A transverse shaft 5 is carried by the boom and is provided, at each end, with a gear 6. These gears mesh with segmental racks 7 secured to the frame A at opposite sides of the boom, the said racks being concentric with the shaft 1. Thus it will be seen that when the boom is swung about its pivoted connection 1 the gears 6 and the shaft 5 will rotate.

Secured to the shaft 5 is a brake wheel 8 and a brake band 9 is mounted in close proximity to the periphery of the wheel. One end of the band is fixedly mounted as shown at 10 while the other end thereof is secured to one end of a lever 11. This lever is fulcrumed between its ends, as shown at 12, and is adapted to be held against movement by a keeper 13 mounted on the boom.

Under normal conditions the band 9 is loose on the wheel 8 and boom 2 can thus be adjusted readily to position at any desired angle relative to the surface of the ground. When the boom has been brought to proper position so that the lower end of the digging mechanism is at the desired depth, the band 9 can be tightened on wheel 8 by means of lever 11. Thus rotation of the gears 6 and shaft 5 will be prevented and the boom will therefore be retained at the angle to which it has been moved. This will result in the digging of a trench of uniform depth through all kinds of soil because upward swinging of the boom when subjected to excessive resistance will be prevented.

It is to be understood that the present invention can be combined with different kinds of digging machines utilizing swinging booms carrying digging mechanisms and obviously changes can be made to adapt the improvements to the different machines.

What is claimed is:—

In a trenching machine the combination with a frame and a shaft journaled thereon, of a boom mounted for angular adjustment about the shaft, means carried by the frame and connected to the boom for adjusting said boom angularly, a rack secured to the frame and having downwardly extended teeth, a

shaft journaled on the boom, a gear carried thereby and constantly in mesh with the rack, said rack constituting a shield for the gear, a brake wheel rotatable with the gear, and a brake band extended about and co-operating with the wheel for holding the gear against rotation, thereby to maintain the

boom in any position to which it might be adjusted angularly.

In testimony that I claim the foregoing ¹⁰ as my own, I have hereto affixed my signature.

CHARLES L. GEORGE.
